UNITED STATES PATENT OFFICE.

ELISHA M. WHITNEY, OF WINCHESTER, MASSACHUSETTS.

WASHBOARD.

1,124,985.

Specification of Letters Patent.

Patented Jan. 12, 1915.

Application filed September 19, 1913. Serial No. 790,701.

To all whom it may concern:

Be it known that I, ELISHA M. WHITNEY, a citizen of the United States, residing at Winchendon, in the county of Worcester and State of Massachusetts, have invented new and useful Improvements in Washboards, of which the following is a specification.

This invention relates to improvements in wash boards and it is directed more particularly to the construction of the rubbing board.

The object of the invention is to provide a rubbing board of strong and inexpensive construction which has suitably differentiated rubbing surfaces of efficient character. In furtherance of this object, the rubbing board consists wholly of a single sheet of zinc or other suitable metal having certain novel structural features whereby it has great intrinsic strength so that no special bracing parts or added plies of reinforcing material are required and whereby its two sides present highly efficient and definitely differentiated rubbing surfaces.

The improved board, aside from being intrinsically inexpensive, may be economically manufactured, not only by reason of the absence of special parts but also by reason of the facility with which the rubbing surfaces may be formed.

The invention is illustrated in the accompanying drawings wherein:

Figure 1 is an elevation of a wash board having a rubbing board made in accordance with the invention; Fig. 2 is a vertical sectional view of the rubbing board; Fig. 3 is a horizontal sectional view thereof on the line 3—3 of Fig. 2.

Similar characters of reference designate corresponding parts throughout the several views.

The rubbing board 1 is composed wholly of a single sheet of zinc or other suitable metal having its opposite sides formed to provide rubbing surfaces A and B characterized essentially by transverse corrugations and alternating grooves but differentiated from one another in that the corrugations 2 of the surface A are relatively sharp at their apices and the grooves 3 of said surface are rounded while the corrugations 4 of the surface B are of regular curvature, being rounded and, hence, relatively smooth at their apices and the grooves 5 of said surface B have sharply defined angles coincid-

ing with the apices of the corrugations 2. The corrugations 2 and 4 are arranged alternately and their concave faces present the grooves 5 and 3 respectively which form parts of the opposite rubbing surface. Both of the rubbing surfaces are provided with indentations at right angles to the corrugations and intersecting the apices of the latter. The indentations of the surface A are designated by 6 and the indentations of the surface B are designated by 7. The indentations of each surface form longitudinal projections at the bases or angles of the grooves of the other surface and the indentations of the corrugations of one surface are preferably arranged in staggered relation to the indentations of the other surface. The indentations 6 and 7 strengthen the rubbing board, increase the frictional rubbing power of its surfaces and promote drainage. The indentations 6 and 7 should be arranged at somewhat frequent intervals and in order that this arrangement may be advantageously carried out without any interference with the differentiation between the two surfaces and without such surface irregularity as might cause tearing of the clothes the indentations 6 which intersect the sharp corrugations 2 are, like said corrugations, narrow, and relatively sharp, while the indentations 7 which intersect the rounded or smooth surface corrugations 4 are relatively wide and shallow and not so sharp or clear in their outline as the indentations 6.

From the foregoing description it will be apparent that the rubbing board although comprising but a single sheet of metal is intrinsically strong and provides two rubbing surfaces of distinctive character which are as sharply differentiated from one another as in those constructions wherein two distinct sheets are used to provide the two rubbing surfaces or such surfaces are formed by molding opposite faces of a vitreous plate.

Having fully described my invention, I claim:

A rubbing board which comprises as an entirety a single sheet of metal having alternating corrugations formed with sharp and rounded or smooth surfaced apices, the corrugations with sharp apices projecting from one side of the sheet and the corrugations with rounded or smooth surfaced apices projecting from the opposite side of the sheet, the corrugations at one side of

the sheet defining grooves which are presented at the opposite side of the sheet alternately between the corrugations thereof, the rubbing board also having indentations intersecting the apices of its corrugations, the indentations for the corrugations with sharp apices being relatively narrow and sharp and the indentations for the corrugations with round or smooth surfaced

apices being relatively wide and less sharply defined than the other indentations.

In testimony whereof I have hereunto set my hand in presence of two subscribing witnesses.

ELISHA M. WHITNEY.
